UNITED STATES PATENT OFFICE.

HENRY A. COHRS, OF CURRIE, MINNESOTA.

WIRE-FENCE CONTROLLER.

1,031,622.

Specification of Letters Patent.

Patented July 2, 1912.

Application filed August 15, 1910. Serial No. 577,241.

To all whom it may concern:

Be it known that I, HENRY A. COHRS, a citizen of the United States, residing at Currie, in the county of Murray and State 5 of Minnesota, have invented certain new and useful Improvements in Wire-Fence Controllers, of which the following is a specification.

This invention relates to an improvement 10 in fence posts, the object being to provide a fence of such a construction as to take up the slack in the strands of wire which connect the posts.

Another object is to so arrange the take-up mechanism that the same may be easily 15 operated by means of a wrench.

In the drawings: Figure 1 is a side elevation of the device. Fig. 2 a sectional view, Fig. 3 a detail view of one of the drum 20 members removed from the post, Fig. 4 a detailed view of the wire securing member.

In the drawings: 10 designates a hollow post member provided with a cement base 11. Arranged on said post are spools 12 on 25 which fit a collar 13 one face of which is provided with the ratchet teeth 14 the barrel 15 of the spool extending to a point adjacent said ratchet teeth. A sleeve 16 is adapted to embrace the post said sleeve extending 30 within the ratchet collar and abutting the end portion of the barrel. This sleeve is rigidly connected to the post and is adapted to support a dog 17 which engages with the teeth on the sleeve.

35 In operation the wire is connected to the attaching device 18 which is secured to the spool. When it is desired to tighten the wire a spanner wrench is made to grip the spool, the spool is then rotated until the wire 40 has been sufficiently tightened. The dog 17 prevents the spool from unwinding.

Any number of these devices may be positioned on the post their number depending upon the number of the strands.

45 The attaching device 18 consists of a screw threaded shank portion and the arms 18', between which the wire is adapted to be slipped, the barb of the wire being adapted to engage the arms 18' or in the event that

barbed wire is not used, the wire is twisted 50 around said arms.

From the foregoing it will be seen that the wire strands may be quickly and conveniently tightened without the hands of the operator coming in contact with the 55 wire.

What is claimed is:

1. The combination with a rounded post, of a pair of flanged collars rotatably mounted thereon and having their flanges in engagement with each other, wire holding members carried by said collars, a similarly shaped flanged collar fitting over the end of each of the collars and secured thereto, said second collar having a toothed edge, a 60 securing collar mounted on the post in engagement with the end of each of the first mentioned flanged collars, means for securing the securing collars in adjusted position on the post, and spring pressed dogs pivoted 65 to the securing collars to engage the teeth of the toothed flanged collars to lock the same against rotative movement. 70

2. The combination with a tubular supporting post, of a sleeve secured thereon, a 75 collar rotatably mounted on the post and resting on said sleeve, said collar having an outwardly extending peripheral flange formed on its upper end, a similarly shaped collar mounted in reverse position on the 80 post and having its flange resting on the flange of the first mentioned collar, a sleeve secured on the post for retaining the collars against upward movement, a flanged collar having a toothed edge secured on each of the 85 other collars with its toothed edge projecting over the adjacent securing sleeve, spring pressed dogs carried by each sleeve for engaging the toothed collar to prevent rotation of the same in but one direction, and 90 wire gripping members secured to and projecting from the collars.

In testimony whereof I affix my signature, in the presence of two witnesses.

HENRY A. COHRS.
